UNITED STATES PATENT OFFICE

CARL G. OLSON, OF CHICAGO, ILLINOIS, ASSIGNOR TO ILLINOIS TOOL WORKS, OF CHICAGO, ILLINOIS, A CORPORATION OF ILLINOIS

HOB FOR CUTTING ROLLER-CHAIN SPROCKETS

Application filed August 29, 1927. Serial No. 216,223.

My invention relates to hobs for generating roller chain sprockets and one of the objects of the invention is to provide a hob which will cut metal more freely than the hobs previously used, thereby enabling the hob to yield an increased output over ordinary hobs and to make practical the cutting of roller chain sprockets of large pitch.

Another object is to provide a hob which at any given moment will act upon the sprocket at a greater number of points than heretofore.

Another object is to provide a hob that will take short chips or cuts at many points rather than longer chips at fewer points, as in previously known hobs.

Another object is to increase the smoothness of operation of the hob and distribute more widely the stresses and strains incident to cutting, thereby relieving the strain on the machine and thus making it possible to feed the work faster and consequently increase the output.

Other characteristics which contribute to the foregoing objects will become apparent from the following description taken in connection with the accompanying drawings in which,

Figure 1 is a side view of a hob embodying the invention.

Figure 2 is an end view thereof.

Figure 3 is a side view of a roller chain sprocket of standard form illustrating the type of work that my new hob is capable of producing. This particular sprocket is not of large pitch but in Figures 4 and 5, sprockets of larger pitch i. e., fewer teeth in proportion to the diameter, are shown, my hob having special utility in producing sprockets of such character.

Figures 4 and 5 are views respectively of known hobs and my new hob placed in juxtaposition for more thoroughly bringing out the contrast.

Like numerals denote identical parts in the several figures.

It is well known that roller chain sprockets as well as other forms of toothed gears may be produced by the molding generating process by the employment of hobs. The teeth of

the sprocket or other toothed member to be produced are laid out upon the basis of a circle which is concentric with the work and commonly termed the generating circle. This generating circle, as it will be herein-after referred to, is commonly coincident with, or approximately of the same diameter as the pitch circle of the work. 55

I have discovered that for the production of roller chain sprockets the hob may be greatly improved by employing as the generating circle one which has a diameter larger than the overall diameter of the work. This produces a hob having a longer lead than in hobs usually employed for the purpose. 65

I have found that by thus increasing the length of the lead the cutting action of the hob will be distributed over a greater arc of the work; will take cuts at more points on the work, and will take cuts that are shorter than those taken by hobs of standard lead. 70

In order to give a practical illustration of the difference between the improved hob and those previously known, I will first refer to Figure 4 in which is shown a hob of conventional form for producing roller chain sprockets. In this view, as in Figure 5, the sprocket teeth A are of standard form, the valleys 10 or bottom of the teeth spaces, being circular in profile. In both views the broken line 12 represents the pitch circle of the sprocket and according to standard specifications now employed in this country, this pitch circle is approximately mid-height of the sprocket teeth. In the old form of hob, 85 the teeth B are developed upon a pitch line 14 which is tangent to the pitch circle 12. In this old type hob the tops of the teeth, that is, the portions lying outside of the pitch line, are circular in profile and almost are semi-circles, this condition being illustrated by comparison with the dotted circle 16 shown near the middle of Figure 4.

The consequence is that with this old type of hob the teeth located near the center of the hob take a long cut, for illustration, a cut extending approximately from the point x through the point y and to the point z, Figure 4. This cut extends almost throughout a semi-circle with the result that the mid-por- 95 100

tion of the hob is called upon to do the major portion of the work while smaller cuts are taken at the points *r* and *s*. It will be understood that Figure 4 is merely illustrative of typical conditions of the old style hob, but it does show that the main burden is imposed upon the mid-portion of the hob with the chief burden imposed upon what may be regarded as the central tooth which cuts throughout an arc of almost 180 degrees.

The result is that unless the cut is comparatively shallow it will cause undue wear and tear upon the hob and the shock as the successive teeth take hold will be excessive. Also the work will be confined to approximately three points on the gear blank and the total result is that the output of a hob of this character is of necessity limited.

Now referring to Figure 5, which illustrates the form and action of my new hob, the teeth *A* of the work remain the same as before owing to the fact that my hob is designed to produce a sprocket of standard form. The hob, however, instead of being developed upon a pitch line 14 tangent to the pitch circle 12 is developed upon a pitch line 18 tangent to a generating circle 20 located considerably outside of the region conventionally considered in developing hobs for any purpose.

In the particular form illustrated this generating circle 20 is considerably outside of the points of the sprocket teeth, in fact is shown to be approximately as far outside of the points of the sprocket teeth as the points of the sprocket teeth are outside of the pitch circle of the sprocket wheel. These proportions may be varied, but nevertheless, a hob of the proportions illustrated has been found to give excellent results.

As a result of increasing the size of the generating circle the lead of the hob is increased as will be readily understood by those familiar with the theory of involute gearing. To take a concrete example, for a sprocket of $1\frac{1}{2}$ pitch the lead of the ordinary hob of today is about 1.517 inches owing to the fact that the links of a roller sprocket chain are straight, whereas the measurement on the sprocket is arcuate. But in a corresponding hob of my construction the lead is about 1.675 inches.

As a result of this increased lead, the central tooth *b*¹ of the new hob will take a much shorter cut at the valley of the teeth, but will simultaneously take cuts at the points *t*, *u* near the points of the adjacent sprocket teeth. In addition to this the tooth *b*² at the left will take a cut at the point *v* on the adjacent sprocket tooth to the left while the hob tooth *b*³ will take a cut at the adjacent tooth *w* to the right. In other words, the new hob will contact and cut the work at five points simultaneously and each of these cuts will be of shorter length than the main or central cut

taken by the old type hobs. This has several advantages, for example, the work will be distributed over a greater length of the hob thus increasing the life of the hob and making it practical to take a somewhat deeper cut. The shock due to contact of the oncoming teeth will also be reduced and the action accordingly rendered smoother. The cutting action will also be spread over a greater arcuate length of the sprocket. In aggregate, however, the lengths of the cuts will be as great as the aggregate lengths of cut taken by the old type of hob.

In Figures 4 and 5, I have for the purpose of explanation shown hobs of greater length than are employed in practice, the additional length at each end being surplausage, but shown for the purpose of better illustrating the theory of construction and operation.

In Figures 1 and 2, I have shown a hob of a length more apt to be used in actual practice it being observed that a hob having a length of three teeth or three turns of the helix is sufficient.

It is desirable that the gashes 20 be helical instead of straight, in accordance with well known practice. It is also desirable that the teeth be hooked, that is be undercut slightly, to exert a shearing cut upon the work. It is good practice to provide an eight per cent hook, approximately, although this may be varied without departing from the spirit of the invention.

In order to more clearly set forth the meaning of the term "generating circle" as used in this application, it might be stated that the generating circle, when associated with the hobbing of sprocket teeth, is an imaginary circle whose circumference is equal to the normal lead of the hob times the number of teeth to be generated in the sprocket. This circle, therefore, is not the base circle nor the pitch circle of the sprocket, as these circles in a sprocket would mean the root circle of the teeth in one instance and a circle passing through the center of the rollers in a chain wrapped around the sprocket in the other instance. The teeth of a sprocket have certain characteristics which differ from the teeth of an involute gear in that the teeth of a sprocket are not generated from a basic rack of a system of gear teeth as is the case in developing involute gears. In fact, the curves in sprocket teeth are not necessarily involute curves, but are more or less arbitrary curves to comply with the rollers of a chain or an aggregate contour of a chain wrapped on and off the sprocket, certain portions of the teeth having clearances outside of the roller seat, which do not contact with the chain at all but are merely guides for the chain. It will thus be apparent that by using the term "generating circle" applicant does not refer specifically to the base circle or the pitch circle of the sprocket. Sprockets of any

number of teeth cannot be generated by the same basic rack as above pointed out, due to the fact that the circular or arcuated pitch differ in sprockets of different diameters or in different numbers of teeth even though the pitch of the chain to run on these sprockets is the same.

I have found that as result of the construction hereinabove described the output of the hob is greatly increased, its life prolonged, smoothness of operation is increased and a wider distribution, axially, of stresses and strains is obtained.

Having thus described my invention what I claim as new and desire to secure by Letters Patents, is:

1. A hob for cutting roller chain sprockets wherein the bottom of the space between the teeth is approximately circular, said hob being developed upon a pitch line corresponding to a generating circle greater than the pitch circle of the sprocket.

2. A hob for generating roller chain sprockets, said hob having its teeth arranged according to a helicoidal thread and of a contour to provide a short contact distance to envelope the teeth of the sprocket when the sprocket is rolling on a circle of a larger diameter than the overall diameter of the sprocket.

3. In a hob for generating roller chain sprockets and the like having a helicoidal thread of a lead greater than the circular pitch of the sprocket to be cut, the pitch line of the hob being tangent to a generating circle located outside of the points of the sprocket teeth.

4. A hob for generating roller chain sprockets, the pitch of the teeth of the hob being greater than the pitch of the sprocket to be cut and adapted to contact the sprocket at more than three separate points simultaneously.

5. A hob for generating roller chain sprockets, the pitch of the teeth of the hob being greater than the pitch of the teeth of the sprocket to be cut and adapted to contact the sprocket at at least five separate points simultaneously.

6. A hob for generating roller chain sprockets, the helical lead of the hob being greater than the pitch of the sprocket to be cut, the profile of the hob teeth being such that the hob tooth opposite the center of the sprocket will engage an arc of less than 120 degrees at the bottom of the tooth space on the sprocket and will simultaneously engage the sprocket teeth at other points remote from said arc.

7. A hob for generating roller chain sprockets, the helical lead of the hob being greater than the pitch of the sprocket to be cut, the profile of the hob teeth being such that the hob tooth opposite the center of the sprocket will engage an arc of less than 120 degrees at the bottom of the tooth space on

the sprocket and will simultaneously engage the adjacent sides of the two teeth adjacent to said space at points separate from said arc.

8. A hob for generating roller chain sprockets, the helical lead of the hob being greater than the pitch of the sprocket to be cut, the profile of the hob teeth being such that the hob tooth opposite the center of the sprocket will engage an arc of less than 120 degrees at the bottom of the tooth space on the sprocket and will simultaneously engage the adjacent side of the two teeth adjacent to said space at points separate from said arc and will simultaneously engage two other sprocket teeth.

9. A hob for generating roller chain sprockets having a helicoidal thread, spiral flutes at right angles to the thread, teeth having cutting edges lying in the helicoidal thread, said thread being configurated to envelope the profile of a roller chain sprocket to be cut when generating on a circle of greater diameter than the sprocket, said thread having a lead conforming to said generating circle, and therefore being expanded longitudinally and the sides of the teeth sloping more gently than in the ordinary hob and the faces of the teeth being undercut to increase the acuteness of said cutting edges.

10. A generating hob for cutting roller chain sprockets, the teeth of said hob being configurated so as to cause them to generate sprocket gear teeth when generating on a circle of larger diameter than the pitch circle of the sprocket to be cut.

11. A generating hob for cutting roller chain sprockets, said hob having its teeth arranged according to a helicoidal thread, and having its teeth so configurated as to cause them to generate sprocket gear teeth when generating on a circle of larger diameter than the pitch circle of the gear to be cut, the front faces of the teeth being undercut to increase the acuteness of the cutting edges thereof.

12. A hob for generating gear teeth, said hob being developed upon a pitch line corresponding to a generating circle greater than the pitch circle of the gear to be cut.

13. A hob for generating sprockets and the like having a helicoidal thread of a lead corresponding to a distance measured along a circle which is of greater diameter than the sprocket to be cut, said distance being taken between a pair of imaginary extended radial lines of the sprocket which intersect said circle, said imaginary lines passing through the pitch circle of the sprocket at points, the distance between which is equal to the circular pitch of the sprocket.

In witness whereof, I have hereunto subscribed my name.

CARL G. OLSON.
